UNITED STATES PATENT OFFICE.

CHARLES V. POLLOCK, OF NEW YORK, N. Y.

DESIGN FOR A RUBBER BAG.

SPECIFICATION forming part of Design No. 25,430, dated April 21, 1896.

Application filed March 17, 1896. Serial No. 583,632. Term of patent 14 years.

To all whom it may concern:

Be it known that I, CHARLES V. POLLOCK, a citizen of the United States, residing at New York, in the county and State of New York, have invented and produced a new and original Design for Rubber Bags, of which the following is a specification, reference being had to the accompanying drawing, showing a part thereof.

- 10 The figure in the drawing shows the front side elevation of the bag, this view alone being deemed sufficient to illustrate my design, as the rear side view of the bag is substantially the same as the front side.
- 15 The general outline of the body of the bag is shield-shaped, the top edge being straight with parallel ribs or bands B B of different widths and thicknesses just below. The side edges are straight and parallel, and the 20 curved bottom has a depending extension D terminating with a nipple. A binding C C extends down the side edges and the curved edges of the bottom to the end of the said extension. The edges of the binding are finely scalloped, and rows of indentations representing stitching appear between the said bands and elsewhere on the bag. A loop A is attached at its ends to the inner side of the back at the mouth of the bag and in an open position.

25 The essential features of this design, whether of the front or rear face, consist of a bag having a shield-shaped outline form, an open mouth extending entirely across the top, and a depending extension at the bottom terminating with a nipple.

30 What I claim is—

The design for a rubber bag substantially as herein shown and described.
